(21) Appl. No.: **29/551,968**

The ornamental design for an electronic limited slip differential with separation of clutch and actuator, as shown and described.

(22) Filed: **Jan. 19, 2016**

DESCRIPTION

(63) Continuation of application No. 29/498,114, filed on Jul. 31, 2014, now Pat. No. Des. 749,135, which is a continuation-in-part of application No. 29/466,469, filed on Sep. 9, 2013, now Pat. No. Des. 741,915.

FIG. 1 is a front perspective view of an electronic limited slip differential with separation of clutch and actuator showing the new design.

(51) **LOC (11) Cl.** **15-01**

FIG. 2 is a front view of the electronic limited slip differential with separation of clutch and actuator of FIG. 1.

(52) **U.S. Cl.**

FIG. 3 is a rear view of the electronic limited slip differential with separation of clutch and actuator of FIG. 1.

USPC **D15/5**

FIG. 4 is a first side view of the electronic limited slip differential with separation of clutch and actuator of FIG. 1.

(58) **Field of Classification Search**

FIG. 5 is a second side view of the electronic limited slip differential with separation of clutch and actuator of FIG. 1.

FIG. 6 is a third side view of the electronic limited slip differential with separation of clutch and actuator of FIG. 1; and,

See application file for complete search history.

FIG. 7 is a fourth side view of the electronic limited slip differential with separation of clutch and actuator of FIG. 1.

(56) **References Cited**

Any portion of the electronic limited slip differential with separation of clutch and actuator shown in broken lines is for the purpose of illustrating environmental structure and forms no part of the claimed design.
